UNITED STATES PATENT OFFICE.

**EDWARD L. KNAPP, OF GRAND RAPIDS, MICHIGAN, ASSIGNOR TO THE NATIONAL
BRASS COMPANY, OF GRAND RAPIDS, MICHIGAN, A CORPORATION OF MICHIGAN.**

DESIGN FOR A DRAWER PULL.

Application filed March 22, 1927. Serial No. 21,254. Term of patent 3½ years.

To all whom it may concern:

Be it known that I, EDWARD L. KNAPP, a citizen of the United States, residing at the city of Grand Rapids, in the county of Kent and State of Michigan, have invented a new, original, and ornamental Design for Drawer Pull, of which the following is a specification, reference being had to the accompanying drawing, forming a part thereof.

Fig. 1 is a plan view of a drawer pull showing my new design, and

Fig. 2 is a side elevation of the same.

I claim:

The ornamental design for a drawer pull, as shown.

EDWARD L. KNAPP.
